UNITED STATES PATENT OFFICE.

FRANK McMURRAY SAWYER, OF ALHAMBRA, CALIFORNIA.

BUILDING CONSTRUCTION.

1,240,492.

Specification of Letters Patent. Patented Sept. 18, 1917.

Application filed February 10, 1915. Serial No. 7,390.

To all whom it may concern:

Be it known that I, FRANK McMURRAY SAWYER, a citizen of the United States, residing at Alhambra, California, have invented a new and useful Building Construction, of which the following is a specification.

This invention pertains to a building construction intended principally for use in the walls of buildings. The standardized slabs of which the wall is chiefly composed are designed to be cast out of a suitable cementitious substance, said slabs being of such contour that after they have been cast they may be assembled in such a manner as to produce a wall of superior strength, durability and general structural merit, the strength and stability of the wall being further secured by the provision of certain hollow piers into which liquid concrete or grout is poured to cement together the structure into one compact, stable whole.

An object of this invention is to construct a hollow wall that will be both light and strong and furnished with improved means to provide the sides of the wall from bulging under the pressure of the liquid grout which is filled into the wall during construction and is allowed to harden in order to cement the assembled parts of the wall together into one solid structure. As an aid to secure this object of the invention, there is provided an improved transverse key slab which is adapted to resist both internal pressure and also external pressure against the sides of the wall, so that the wall will neither be ruptured from the building materials contained within its sides, nor will it be collapsed by external pressure.

To further strengthen the wall a metal reinforcement may be incorporated at such points as may be desired in both vertical and horizontal directions.

Referring to the accompanying drawings, which illustrate the invention, Figure 1 is an isometrical view of a wall, certain slabs being broken away to show more clearly the means for binding the wall together.

Fig. 2 is an isometrical view of one of the key slabs.

Fig. 3 is an isometrical view of a key-slab having a double abutment to provide for inserting a secondary longitudinal slab required in the formation of additional cement piers.

Fig. 4 is an isometrical view showing the

internal face of one of the longitudinal slabs.

Fig. 5 is an isometrical view showing an external face of the slab shown in Fig. 4.

Fig. 6 is an isometrical view of an internal longitudinal slab.

Fig. 7 is a partial longitudinal section through the concrete contained in the longitudinal pockets of Fig. 1.

Referring in detail to the drawings, each outer side portion of the wall consists of a series of slabs 9 arranged in longitudinal and in vertical courses, thus forming two sets, designated in Fig. 1 as an inner set A and an outer set B. These sets of the slabs 9 are arranged parallel to each other, a slab 9 of one set being placed opposite to a corresponding slab 9 of the other set, thus forming pairs of slabs the members of which 75 pairs are held together by the transverse key slabs 11 and 11^a.

Each member of said pairs of slabs 9 is provided with end extensions 12, the extension 12 at one end being preferably at the upper edge and the extension 12 at the other end preferably being at the lower edge. These end extensions 12 of adjacent slabs 9 overlap each other in an edgewise manner, the end of each slab 9 being slightly spaced 85 away from the end of the next slab 9 of the same horizontal course, thus leaving two vertical spaces or slots between the ends of adjacent slabs of the same horizontal course. These spaces are spaced longitudinally apart 90 with respect to the wall, one of said spaces being at the upper edge of the course and the other of said spaces or slots being at the lower edge of the course. It will be understood, however, that these spaces are never 95 left open, but as fast as the wall is assembled they are filled with the ends of the key slabs 11 next described.

The transversely extending key slabs 11 are arranged in pairs, the members of said 100 pairs each having end extensions 14, preferably diagonally opposite to each other, which project into and fill the vertical spaces already referred to between the ends of the slabs 9. Each extension 14 of the key slabs 105 has at its inner edge an overhanging shoulder or interlocking lug 15 which engages the base of the locking ledge 16 with which each of the slabs 9 is provided. Said ledge 16 is beveled or inclined from side to side to correspond with the inclination of the face of the interlocking lug 15 of the key slab 11.

Said key slab 11 is provided with an abutment 17, the length of the extension 14 preferably being the same as the thickness of the slab 9, so that when the key slabs are fitted in place the abutments 17 fit against the inner sides of the slabs 9 and the ends of extensions 14 are flush with the surface of the wall.

By this construction there is provided between the members of the pairs of key slabs 10 11, space for filling in the cement to form the cement piers 18, through which may also extend the vertical reinforcements 19.

When it is desired to provide pockets 20 for concrete filling longitudinally of the 15 wall, key slabs 11^a are provided leaving the extensions 14^a and shoulders 15^a with an additional right angled recess 21. Said recess 21 cooperates with an inner set of longitudinally placed slabs 9^a which have end 20 projections 22. Said projections 22 seat at the bases of the said recesses 21, of the key slabs 11^a. Said pockets 20 are filled with cementitious substance, as illustrated in Figs. 1 and 7. The cement in these pockets is continuous in a zigzag manner longitudinally of the wall, and is also continuous vertically. The recesses 21 extend toward the centers of slabs 11^a far enough to provide that when the end portions of the longitudinally placed 30 slabs 9^a are abutted against the inner sides of said recesses 21, there is left between each slab 9^a and the adjacent slab 9, sufficient space to form a space or pocket 20 of the desired width.

95 Owing to the edgewise overlapping of the end of slabs 9, a considerable portion of the inner face of each of said overlapping slabs is brought into contact with the adhesive material constituting the adjacent pier, thus 40 forming a bond or union between adjacent slabs of the same longitudinal course, the cement bond being made more effective by the use of the depressions 25, which are arranged diagonally opposite to each other, 45 thus bringing said depressions in line with the transversely extending portions of the cement filling.

In case both the long edges of slabs 9 are made beveled, as shown in the illustrated 50 embodiment of the invention, there will be left V-joints 26 along the faces of the wall which act as a key for plaster or to receive the mortar for the finished joint.

In some cases it may be preferable to use 55 metal instead of precast concrete in the formation of the key slabs 11 and 11^a, but changes of this character, it will be seen, fall within the scope of the appended claims.

60 In order to cement the side slabs 9 more securely in place, each of said slabs is pro-

vided with an irregularity on its internal face, this irregularity, in the illustrated embodiment of the invention consisting of a depression 25 into which the cement projects in order to bind the slab more securely in place.

The slabs 9 are preferably provided with beveled upper and lower edges thereby providing V-shaped joints 26 along the faces 70 of the wall which may be filled with mortar in order to seal the joints.

I claim:

1. In a wall, two sets of slabs, each of said sets comprising an inner and an outer course of longitudinally extending slabs arranged to form the side portions of the wall and to leave a space extending longitudinally along each side of the wall between the inner and outer slabs of said sets of 80 slabs, the outer course of slabs at each side of the wall having end extensions which overlap each other in an edgewise manner, there being a vertically extending space at the end of each of said overlapping extensions to receive a key slab, key slabs extending across the wall and fitting into said spaces at each side thereof, said extensions being of sufficient length to separate said key slabs longitudinally of the wall to form 90 cement-receiving pockets or spaces, and a filling of adhesive cement occupying said pockets or spaces.

2. In a wall, slabs extending lengthwise of the wall at each of its outer sides, the 95 slabs at each side of the wall being arranged in horizontal courses in which contiguous slabs are provided with end extensions which overlap in an edgewise manner and are slightly spaced apart from each other 100 lengthwise of the wall, key slabs the ends of which occupy the spaces thus provided at each side of the wall, said key slabs being arranged in pairs the members of which are spaced apart lengthwise of the wall by 105 reason of one member of each pair occupying the space at the end of one longitudinal slab and the other member occupying the space at the end of the adjacent overlapping extension of the contiguous slab, and a filling of adhesive cement occupying the spaces between the members of said pairs of key slabs.

In testimony whereof I have hereunto signed my name in the presence of two subscribing witnesses at Los Angeles, in the county of Los Angeles and State of California, this fifth day of February 1915.

FRANK McMURRAY SAWYER.
